(57) **CLAIM**

The ornamental design for a wall mountable support, as shown and described.

DESCRIPTION

In a preferred embodiment, the nature of this product is a wall mountable support such as can be used with a robe hook and a vertically oriented toilet paper holder.

FIG. 1 is a left, top, front perspective view of a wall mountable support according to my new design;

FIG. 2 is a front elevational view thereof;

FIG. 3 is a left side elevational view thereof, the right side elevational view thereof being a mirror image the left side shown;

FIG. 4 is a top plan view thereof;

FIG. 5 is a bottom plan view thereof;

FIG. 6 is a rear elevational view thereof;

FIG. 7 is a left, top, front perspective view of a wall mountable support according to another embodiment of my new design;

FIG. 8 is a front elevational view thereof;

FIG. 9 is a left side elevational view thereof, the right side elevational view thereof being a mirror image the left side shown;

FIG. 10 is a top plan view thereof;

FIG. 11 is a bottom plan view thereof; and,

FIG. 12 is a rear elevational view thereof.

The broken line representations of bar environment in FIGS. 1-5, holder environment in FIGS. 7-12, and rear bracket structure in FIGS. 6 and 12 are for the purpose of illustration only, and form no part of the claimed design.
